US00D623164S

(12) **United States Design Patent**
Wang et al.

(10) **Patent No.:** US D623,164 S
(45) **Date of Patent:** ** Sep. 7, 2010

(54) **MOBILE PHONE**

(75) Inventors: **Ying-Zhuo Wang**, Shenzhen (CN);
Hsiao-Hua Tu, Shindian (TW)

(73) Assignee: **FIH (Hong Kong) Limited**, Kowloon
(HK)

(**) Term: **14 Years**

(21) Appl. No.: **29/352,142**

(22) Filed: **Dec. 17, 2009**

(30) **Foreign Application Priority Data**

Jun. 19, 2009 (CN) 2009 3 0306631

(51) **LOC (9) Cl.** 14-03

(52) **U.S. Cl.** ..... **D14/138 AD**

(57) **CLAIM**

The ornamental design for a mobile phone, as shown and described.

DESCRIPTION

FIG. 1 is a perspective view of a mobile phone showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 and FIG. 9 are views of alternative configurations of the mobile phone of FIG. 1.

The broken lines immediately adjacent the claimed areas represent the bounds of the claimed design while all other broken lines are directed to environment and are for illustrative purposes only; the broken lines form no part of the claimed design.

1 Claim, 9 Drawing Sheets
